ELIE F. G. H. FAURE, OF ERIE, PENNSYLVANIA, ASSIGNOR TO BURKE ELECTRIC COMPANY, A CORPORATION OF PENNSYLVANIA.

SWITCH MECHANISM.

1,271,555.

Specification of Letters Patent.

Patented July 9, 1918.

Application filed March 17, 1914. Serial No. 825,377.

To all whom it may concern:

Be it known that I, ELIE F. G. H. FAURE, a citizen of the United States, residing at Erie, in the county of Erie and State of Pennsylvania, have invented certain new and useful Improvements in Switch Mechanism, of which the following is a full, clear, and exact specification.

This invention relates to quick acting reciprocating mechanism, and has particular reference to means for causing a reciprocating bar to move quickly in one or both directions, and independently of the controlling device.

The device essentially comprises a reciprocating rod, bar or other part combined with a spring, latching means and a controlling device in such manner that the controlling device is first moved to exert a tension upon the spring tending to throw the reciprocating member, and then after a predetermined movement causing the latching means to be released and thereby permit the spring with its accumulated energy to quickly throw the reciprocating member. It will thus be seen that the device is characterized by a controlling means which has a preliminary movement independent of the reciprocating member and during which energy is stored for actuating the reciprocating member after the controlling means has moved a predetermined distance and released the latch. The device is capable of use in many relations, and is particularly shown herein for actuating a switch to control the circuit of an electrical translating device such as a motor. As heretofore specifically applied, the device has been employed to control the circuit of a portable electric drill. Portable electric drills are extensively used for drilling ship and structural shapes, plates and the like, and are subjected to rough and frequently unintelligent use. Difficulty has been experienced in devising controlling switch mechanisms for these drills, which would properly and quickly open and close the motor circuit. It is often necessary to quickly stop the drill and ordinary switches work too slow

and do not always give sufficient break to 50 avoid destructive arcs. It is, therefore, an object of this invention to provide a switch mechanism which will open and close with equal rapidity, and which can be proportioned to give as much break as may be desired, without either involving slow operation or being dependent upon the will of the operator. It is, therefore, impossible for him either to leave the switch partly closed when he intends to close it or partly open 60 when he intends to open it, since no movement of the switch in either direction takes place until the latch is released, and when once the latch is released the switch is beyond control by the operator until its movement by the spring has been effected.

The specific form of the invention shown herein embodies the foregoing characteristics, and in addition there is shown an additional spring acting on the controlling 70 means, and causing it to tend to automatically return and open the switch, unless resisted by the hand of the operator. Thus, if the operator lets go of the controlling handle, the switch automatically opens. Obviously, the reverse operation could be effected, that is the switch could be biased by 75 the spring to close and be held open by the hand of the operator.

In the accompanying drawing, 80 Figure 1 is a longitudinal section of a mechanism embodying the invention, showing the switch open;

Fig. 2 shows a different position, in which the controlling handle is about to trip the 85 reciprocating bar to open the switch; and

Fig. 3 shows a detail of the switch mechanism at right angles to Fig. 1.

1 represents a tubular casing or handle which will be attached at its lower end 2 to the frame of the drill, drill, motor, chuck and associated parts not being shown herein. 3 represents a reciprocating bar only used for tripping, and at its forward end carrying a pin 5 which passes through a slot 6 in a plunger 7. The plunger 7 carries a rod 8 which latter carries a cross-head 9, to which is fastened through insulating plates

10 the movable switch member 11. This bridges the circuit across two spring contacts 12 having circuit terminals 13. The cross-head 9 has a slot which engages with 5 a pin 14 so as to prevent rotation thereof in the handle 1. 15 is the power supply cable which runs into a bushing 16 which is held to the casing by a clamp 17, and the wires go to a blowout magnet 18 and thence to the 10 terminals 13. It will be seen that one side of the circuit is opened by this arrangement, producing a double break. A double break on each side can also be made.

The reciprocating member or bar 3 is movable transversely to its path of reciprocation, the front end moving in the slot 6 of the plunger. The pivoting point is at stop 21 for the return movement, and at stop 22 for the forward movement, and the roller 4 reduces the friction when the controlling lever bears on it to disengage notch 20 from latch 21. The bar 3 carries two notches 19, 20, which respectively engage with fixed stops 21, 22. The bar 3 is also provided with a 15 pin 23 to which is attached a spring 24, the other end of the spring 24 being attached at 25 to the controlling lever 26, which is pivoted on the casing 1 at 27. The bar 3 is 20 also provided with a tripping projection 28 which will be engaged by the corner 29 of the controlling device 26. It will also be observed that the pivot 25 swings in an arc 25 about pivot 27, and thereby causes the spring 24 to tend to throw the bar 3 in one or the other direction depending upon which side of pivot 27 the pin 23 is on.

In the position shown in Fig. 1, the mechanism is in off position, with the spring 24 under slight tension and tending to hold the 40 controlling device 26 in its extreme left position. At the same time, the notch 19 of bar 3 is engaged with stop 21. Upon moving the controlling device 26 to the right, it will be seen that the first effect is to put increasing tension on the spring 24, as the lever 26 moves to the right, but the latch 19 holds the bar 3 against movement to the right until the corner 29 of the controlling lever 26 engages the bar 3 at projection 28 50 and disengages the notch 19 from the latch 21. Thereupon, the spring 24 quickly throws the entire reciprocating mechanism to the right, causing a very quick and rapid engagement of the switch contacts 11 and 12. 55 It will be seen that the actual movement of the switch does not commence until the bar 3 is tripped at 19, and thereupon, the spring moves it beyond the possibility of any control by the operator, and quicker than the 60 operator could possibly try to stop it or fail to properly trip it. Fig. 2 shows the position of the controlling lever 26 just as it engages roller 4 showing that the controlling lever has nearly completed its move-

ment without moving the switch. When the 65 switch is closed, the notch 20 engages with the stop 22, because the tension of the spring 24 tends to always lift the bar 3 and cause it to slide under the stops 21, 22.

Should the operator now let go of handle 70 26 after the bar has been tripped and the switch closed, spring 31 connected at one end to the casing at 32 and at its other end to the lever 26 at 33, would pull the lever 26 backward and cause it to trip the notch 75 20 from stop 22 by again engaging the bar 3 (or the roller 4) at the curve 34. Obviously, the spring 31 can be omitted, so that the switch would remain closed until the operator throws lever 26 to the left far 80 enough to engage curve 34 of the lever with the roller 4 of bar 3 and depress it so as to disengage stop 22 from notch 20, whereupon the spring 24 would throw the entire reciprocating mechanism back to its original position, opening the switch. 85

The casing 1 is suitably formed at its forward end to contain the blowout magnet 18, the necessary circuit terminals, etc., and the switch contacts 11 and 12 are preferably 90 inclosed in a non-combustible casing 35 so that the arcs will be confined therein and not damage other parts.

It is thought that the nature and advantages of the quick acting reciprocating mechanism herein described will be fully understood without further explanation. Inasmuch as the apparatus is capable of use in numerous relations I do not restrict myself 95 either to its specific use in a switch, nor 100 do I restrict myself to the precise details of construction and arrangement of parts herein illustrated, as various modifications and changes can be made therein without departing from the scope of the appended 105 claims.

Having thus described my invention, I declare that what I claim as new and desire to secure by Letters Patent, is:—

1. A switch mechanism comprising a tubular handle, a switch member longitudinally and laterally movable therein, a control member mounted on said handle and a spring between said switch and said control member for snapping said switch longitudinally to extreme position and laterally to latch it in said position. 110

2. A switch mechanism comprising a longitudinally and laterally movable switch bar reciprocating between opposite extreme positions, latching means engaged by lateral movement of said bar, a control member, and a power storing spring between said control member and said bar for snapping said bar longitudinally to extreme position and laterally to latch it in said position. 115 120

3. The combination with a movable switch member, of a switch bar slidably pivoted

thereto, latching means engaging the respective ends of said bar, a controlling device movable to release said bar from said stops, and a spring connected between said device 5 and said bar for moving said switch member when said bar is released.

4. The combination with a tubular housing, of a switch member longitudinally reciprocating therein, a latching bar attached 10 to said switch member, latching means interlocking with said bar, an external controlling device carried by said housing and movable to release said bar from said latching means, and a spring connected to said bar 15 and said controlling device for holding said bar in engagement with said latching means and storing power during movement of said controlling device to actuate said switch member when said bar is released from said 20 latching means.

5. The combination with a tubular housing, of a switch member longitudinally reciprocating therein, a latching bar attached to said switch member, latching means interlocking with said bar, a hollow controlling lever mounted on said housing, and a spring connected at one end within said lever and at the other end to said bar for actuating 25 said switch member when said bar is released.

6. In a quick acting switch mechanism, a bodily movable switch actuating member, a controlling member movable to engage said actuating member, a spring connected between said members and, when moved by said controlling member, storing power for actuating said other member, latching means for holding said actuating member against said stored power, said actuating member 35 being moved laterally and disengaged from said latch when said controlling member is operated.

7. In a switch apparatus, the combination of a longitudinally and laterally movable 40 switch member, latching means interlocking therewith, and a controlling spring for reciprocating said member and interlocking it with said latching means at the end of its reciprocation.

50 8. In a switch mechanism, a longitudinally movable switch bar, latching means interlocking with said bar, a controlling device engaging and moving said bar to release it from said latching means, and a power storing spring connection between said controlling device and said bar and acting both to move the bar when unlatched and latch in its new position.

9. In a switch mechanism, the combination 60 with a tubular handle having a longitudinally reciprocating switch member therein, of latching means mounted on said handle and engaging said switch member to hold it against movement, a controlling lever on

said handle movable with relation to said latching means to release said member from said latching means, and a power storing spring connection between said lever and said switch member and moving said member upon its release from said latching 65 means.

10. The combination with a support having separated stops mounted thereon, of a longitudinally reciprocating bar bearing on said stops and engaging therewith at its respective limits of movement, a controlling lever mounted on said support and having means for disengaging said reciprocating bar from said stops, and a spring connected 75 between said bar and said lever for actuating said bar when disengaged from either of said stops.

11. The combination with a longitudinally movable switch bar, of latching means for said bar at a plurality of positions, a controlling handle movable to disengage said latching means, and a coiled tension spring connected between said bar and said handle to swing in opposite directions about its point of connection to said bar whereby to 80 store power to move said bar upon release of said latching means.

12. In a switch mechanism, the combination with a tubular support, of a switch bar longitudinally movable therein, stationary 95 switch contacts coöperating with said bar, latching means for said bar, a controlling lever projecting from an intermediate portion of said support and adapted to engage said bar and release it from said latching 100 means, and a spring connected at one end to said lever and at the other end to said bar so that said spring will swing to opposite sides of its connection to said bar and simultaneously store power to actuate said bar 105 upon release of said latching means.

13. The combination with a switch member longitudinally movable between opposite extreme positions, of a latching bar pivoted thereto, means for engaging and latching said bar at each position, a movable controlling device for disengaging said bar, a spring connected between said bar and said controlling device for actuating said bar and switch member by power stored in said 110 spring during actuation of said controlling device, and a spring for normally holding said controlling device in one position.

14. The combination with a support having separated stops mounted thereon, of a longitudinally reciprocating bar bearing on said stops and engaging therewith at its respective limits of movement, a controlling lever mounted on said support and having means for disengaging said reciprocating 115 bar from said stops, a spring connected between said bar and said lever for actuating said bar when disengaged from either of 120 125

said stops, and a spring for normally holding said controlling device in off position.

15. A switch mechanism comprising a movable bar, latching means interlocking therewith, a controlling device, a single spring connected to said bar and controlled by said controlling device whereby to both latch said bar and to throw it when un-

latched, and a spring for normally holding said controlling device in off position. 10

In testimony whereof I affix my signature in presence of two witnesses.
